SWINGING HEAD PRESSES

Thomas F. Stacy, Piqua, Ohio, assignor to The French Oil Mill Machinery Company, Piqua, Ohio

Application April 12, 1955, Serial No. 500,790

10 Claims. (Cl. 18—16)

This invention relates to swinging head presses that are usually hydraulically operated and which are sometimes also referred to as hot plate presses. It is in the nature of an improvement upon my prior Patent #2,692,407, granted October 26, 1954.

In the type of press shown in my said United States patent, the upper mold is moved, after a pressing operation, into a forward or out position, in which its normally lower face is disposed to face forwardly and downwardly for ready access in removing pressed objects and preparing the mold for another pressing operation.

An object of this invention is to provide an improved and simple molding press of the swinging head type, with which the upper mold part may be moved into a position in which its lower face is easily accessible between pressing operations; with which the press head and mold part carried thereby may be moved quickly and easily into a readily accessible position or returned to pressing position; with which pressure on the head will be uniformly distributed to the frame of the press during a pressing operation, and which will be relatively simple, strong, sturdy, compact, durable and inexpensive in construction.

Various other objects and advantages will be apparent from the following description of two embodiments of the invention, and the novel features will be particularly pointed out hereinafter in connection with the appended claims.

In the accompanying drawing:

Fig. 1 is a front elevation of a press constructed in accordance with this invention;

Fig. 2 is a side elevation of the same;

Fig. 3 is a sectional elevation of the same from front to rear, but with the pressing head and the upper mold part in the relative positions occupied between pressing operations; and

Fig. 4 is a sectional elevation of the upper part of the press, somewhat similar to the upper part of Fig. 3, but showing a modification of the invention.

In the embodiment of the invention illustrated in Figs. 1 to 3, the press includes a base 1 having incorporated therein a large, hydraulic ram cylinder 2 in the open top of which a main ram or piston 3 reciprocates. Heavy metal plates 4 are secured to the opposite sides of the base 1 and extend upwardly and from the base in parallel relation, and at their upper ends are connected by cross members 5 so that the cross members 5, the side plates 4 and the base 1, together form a basic frame for the press. This type of press is sometimes known as a side plate press. The side plates 4 are secured to the base 1 by screw fasteners 6, and the cross members 5 in the form of tie rods 7 secure the upper ends of the side plates by nuts.

Guided by the side plates and disposed between them is a platen 8 upon which a plate 9 is slidably mounted by means of rollers 9a. The plate 9 serves as a support for a lower mold 10. Disposed along the inside face of each side plate 4 at the top thereof, is a resistance block

11, and the part of the side plate against which the resistance block abuts is provided with a notch having a downwardly facing shoulder 12. The resistance block is somewhat L shaped, with the base of the L fitting into the notch in the side plate and engaged with the shoulder 12, as shown in Fig. 1. This interfitting of the base of each block 11 with the downwardly facing shoulder on the side plate it abuts serves to take up pressure on the resistance blocks during a pressing operation, as will be explained presently. Spacing bars 13 extend between the resistance blocks at their front and rear, and along their lower edges.

Disposed against the underface of the resistance blocks is a pressing head 14 whose upper face abuts against the underfaces of the resistance blocks from front to rear of the latter, and a trunnion 15 passes through the side plates and the pressing head 14 at a point between the front face of the head 14 and the center, from front to rear of the head, so as to serve as a pivot or fulcrum on which the head 14 can rock, with the rear of the head 14 swinging downwardly and forwardly, or rearwardly and upwardly. The resistance blocks 11 do not extend for the full distance from front to rear of the side plates but have their rear faces approximately aligned with the rear faces of the side plates, and extend forwardly nearly to a vertical plane through the axis of the trunnion, and much farther than the middle of the head 14. With this arrangement the head 14 may be rocked on the trunnion 15, from the position shown in Fig. 2 to the position shown in Fig. 3, without the upper face of the head 14 striking the front corner edge of the resistance blocks 11.

The upper face of the head 14 is provided, near its rear, and approximately at the center from side to side, with a lug 16, and a link 17 is pivoted at one end to the lug 16 by a pivot pin 18. The other end of the link 17 is connected to a piston 19 that extends outwardly from a hydraulic cylinder 20 which is pivoted on a trunnion 21 near the forward end of the cylinder. The cylinder 20 is part of a double acting hydraulic or pneumatic motor having pipes 22 and 23 leading to opposite ends of the chamber of the cylinder, which would be on opposite sides of the head (not shown) that is provided on the inner end of the piston rod 19. When fluid pressure is admitted to the upper end of cylinder 20 through the pipe 22 and the pipe 23 is vented, the piston rod 19 will be moved downwardly, and through the link 17, will rock the head 14 from the Fig. 2 position to the Fig. 3 position, and the cylinder 20 may rock on its pivot 21 to accommodate itself to the rocking movement of the head 14. Then the pipe 22 is vented and fluid pressure is admitted through pipe 23 to the lower end of cylinder 20, the piston rod 19 will be forced upwardly by the fluid pressure in piston 20, and this will rock the head 14 from the Fig. 3 position to the Fig. 2 position, in which the upper face of the head 14 will abut flat against the lower faces of the resistance blocks 11 from front to rear of the latter. Since the resistance blocks extend from the rear of the head 14 more than half way toward its front, the pressure on the head during a pressing operation will be carried entirely by the resistance blocks 11 and not by the trunnion 15.

If desired, there may be a slight amount of play or looseness between the trunnion and either the head 14 or side plates 4, so that if there is any inaccuracy in the manufacture of the pressing head when the head is in the Fig. 2 position, it will abut uniformly against the underface of the resistance blocks and will release the trunnion 15 from any substantial pressing pressure. The upper mold section 24 is secured to the lower face of the head 14 so as to move therewith, and when in the inclined position shown in Fig. 3, its lower face will be exposed forwardly and downwardly for access as usual in

this type of press. The head may carry any suitable knock-out device 25 which is usually pneumatically operated and which operates a knock-out rod 26, as usual in this type of press, but since those details of the knock-out cylinder and rod are not particularly a part of this invention, they have been illustrated only schematically.

The plate 9 which is provided on the upper face of the platen 8 may be shifted forwardly in a horizontal direction by a piston 27 which extends into and is operated by a pneumatic cylinder 28 mounted on a bracket 29 that extends from the rear of the frame. This operation of the plate 9 on the platen 8 is shown in my prior Patent #2,692,407, to which reference may be had for a further disclosure of the details thereof, since the present invention relates to a different manner of mounting the head 14 for swinging from its pressing position in Fig. 2 to its inactive position shown in Fig. 3. The platen may be operated into its retracted position by pushback rams 30, as in said prior patent.

In Fig. 4 the resistance blocks 11a extend entirely from front to rear of the side plates and the head 14a, which is mounted on the trunnion 15, has its forward, upper corner bevelled or cut off, as at 31, so that when the head 14a is swung into its inclined position, shown in Fig. 4, its forward, upper corner edge will clear and not strike against the underface of the resistance blocks 11a and interfere with this rocking movement of the head on the trunnion. When the head 14a is in its normal pressing position, its upper face will abut uniformly against the lower faces of the resistance blocks 11a from the rear of the side plates approximately to a vertical plane through the axis of the trunnion 15, which is well forwardly of the middle of the head 14a in a direction from the rear to the front. In this manner the trunnion will be relieved of heavy pressure during a pressing operation, as explained for Figs. 1 to 3.

It will be noted that the front to back dimension of each resistance block is greater than half the width of the rockable head 14, and because of the slight looseness in the trunnion, the load on the face of the rocking head will be uniformly distributed over the underface of the resistance blocks from front to rear.

In the operation of the press, after a product has been molded between the upper and lower molds 10 and 24, and the platen 8 has returned to its fully open position, the cylinders 20 and 28 are operated by fluid pressure to rock the head 14 into the inclined position and to shift the plate 9 on the platen 8 forwardly on suitable rollers, so that the upper face of the lower mold 10 and the lower face of the upper mold 24 will be exposed for ready accessibility for unloading and loading. After the mold sections are loaded, the cylinders 20 and 28 will be active in the reverse direction, which returns the bottom mold 10 to its normal pressing position over the platen, and the head 14 is revolved back to its normal, horizontal position, in which it abuts against the underface of the resistance blocks 3. When both the upper and lower molds are in these pressing positions, hydraulic pressure is applied to the main ram cylinder 2 and the press closes for a molding operation.

It will be understood that suitable limit switches will be disposed in the path of the head 14 and the plate 9, so as to be actuated when the head 14 and the plate 9 resume their normal pressing positions to complete a circuit which controls the delivery of fluid under pressure to the main cylinder 2. In this manner the press cannot be closed until the rocking head 14 and the plate 9 are in pressing positions. The hydraulic circuits controlling the cylinders 20 and 28 are not illustrated because such circuits are common in the industry for controlling double acting, hydraulic motors. Usually a reversing four-way valve is applied to the controls of each of these cylinders 20 and 28 and, if desired, the controls for the cylinders 20 and 28 may be rendered inactive when platen 8 is away from its retracted position.

It will be understood that various changes in the details and arrangements of parts which have been herein described and illustrated in order to explain the nature of the invention may be made by those skilled in the art within the principle and scope of the invention as expressed in the appended claims.

I claim:

1. In a swinging head press of the type in which a pressing platen is moved toward and from a pressing head, that improvement which comprises a frame having spaced side members connected at their ends, a head disposed between said members near one end of said frame, a trunnion passing through said head and said side members and on the axis of which said head may rock, said trunnion being disposed between the front of the head and its median point from front to rear, a resistance block disposed along and secured to each frame side member and extending from the rear of the head approximately to said trunnion in positions to be engaged evenly from front to rear by the head when the latter is in pressing position crosswise of the length of the frame, and means connected to said head to swing it from a pressing position abutting flat against said resistance blocks to an inclined position in which its lower face is inclined and faces forwardly and downwardly.
2. In a hot plate press of the type in which a platen is advanced into and out of pressing engagement with a pressing head, that improvement which comprises said head, a frame having spaced apart but parallel side members connected at their ends, with said head disposed between said members adjacent one end of said frame, said frame having resistance abutments at said one end of said frame attached thereto and against which said head abuts when in pressing position, a trunnion passing through said head and frame side members and rockably mounting said head to swing about the trunnion axis away from said pressing position against said abutments into an inclined position with its pressing surface facing forwardly, said trunnion being disposed between the front of the head and its median point from front to rear, and said head and resistance abutments having clearance space between them forwardly of the trunnions to enable the head to rock on said trunnion between its pressing and inclined positions, and means for rocking said head in both directions between its said positions.
3. In a hot plate press having a frame with spaced, parallel side members connected at the ends of the frame, a pressing head adjacent one end of the frame and between the side members thereof, and a platen movable toward and from said head, the combination therewith of a trunnion passing between and supported by said side members and also through said head between the front of the head and at its center from front to rear to rockably confine said head to said frame, said frame having resistance abutments at said one end beyond said head and flat against which said head abuts when its lower face is normal to the length of the frame, the face of said head adjacent said abutments and said frame having between them sufficient clearance space forwardly of said trunnion to permit said head to rock on said trunnion from its pressing position flat against said abutments and an inclined position with its face towards said platen facing forwardly and downwardly, and means for causing rocking of said head in both directions between its said positions.
4. A hot plate press having a frame with spaced, parallel side members connected at the ends of the frame, a pressing head adjacent one end of the frame and between the side members thereof, and a platen movable toward and from said head, the combination therewith of a trunnion passing between and supported by said side members and also through said head between the front of the head and at its center from front to rear to rockably confine said head to said frame, said frame having resistance abutments at said one end beyond said head and flat against which said head abuts when its lower face is normal to

the length of the frame, the face of said head adjacent said abutments and said frame having between them sufficient clearance space forwardly of said trunnion to permit said head to rock on said trunnion from its pressing position flat against said abutments and an inclined position with its face towards said platen facing forwardly and downwardly, and a fluid operated motor carried by said frame and connected to the rear of said head for rocking the head selectively between its said positions.

5. In a hot plate press having a frame with spaced, parallel side members connected at the ends of the frame, a pressing head adjacent one end of the frame and between the side members thereof, and a platen movable toward and from said head, the combination therewith of a trunnion passing between and supported by said side members and also through said head between the front of the head and at its center from front to rear to rockably confine said head to said frame, said frame having resistance abutments at said one end beyond said head and flat against which said head abuts when its lower face is normal to the length of the frame, the face of said head adjacent said abutments and said frame having between them sufficient clearance space forwardly of said trunnion to permit said head to rock on said trunnion from its pressing position flat against said abutments and an inclined position with its face towards said platen facing forwardly and downwardly, the front to rear dimension of said abutments that are engaged by said head being greater than half the front to rear dimension of that face of the head which abuts said abutments to relieve the trunnion of the pressing load, said trunnion and head having sufficient play to permit the head to engage flatly against said abutments when the head is in its pressing position, and means for causing rocking of said head in both directions between its said positions.

6. In a hot plate press having a frame with spaced, parallel side members connected at the ends of the frame, a pressing head adjacent one end of the frame and between the side members thereof, and a platen movable toward and from said head, the combination therewith of a trunnion passing between and supported by said side members and also through said head between the front of the head and at its center from front to rear to rockably confine said head to said frame, said frame having resistance abutments at said one end beyond said head and flat against which said head abuts when its lower face is normal to the length of the frame, the face of said head adjacent said abutments and said frame having between them sufficient clearance space forwardly of said trunnion to permit said head to rock on said trunnion from its pressing position flat against said abutments and an inclined position with its face towards said platen facing forwardly and downwardly, said trunnion and head having sufficient play to permit the head to engage flatly against said abutments when the head is in its pressing position, and means for causing rocking of said head in both directions between its said positions.

7. In a hot plate press having a frame with spaced, parallel side members connected at the ends of the frame, a pressing head adjacent one end of the frame and between the side members thereof, and a platen movable toward and from said head, the combination therewith of a trunnion passing between and supported by said side members and also through said head between the front of the head and at its center from front to rear to rockably confine said head to said frame, said frame having resistance abutments at said one end beyond said head and flat against which said head abuts when its lower face is normal to the length of the frame, the face of said head adjacent said abutments and said frame having between them sufficient clearance space forwardly of said

trunnion to permit said head to rock on said trunnion from its pressing position flat against said abutments and an inclined position with its face towards said platen facing forwardly and downwardly, the front to rear dimension of said abutments that are engaged by said head being greater than half the front to rear dimension of that face of the head which abuts said abutments to relieve the trunnion of the pressing load, said trunnion and head having sufficient play to permit the head to engage flatly against said abutments when the head is in its pressing position, and means for causing rocking of said head in both directions between its said positions.

8. In a swinging head press of the type in which a pressing platen is moved toward and from a pressing head, that improvement which comprises a frame having abutments near one end thereof, a head disposed below but near said abutments, a trunnion carried by said frame and extending in a direction from side to side thereof and rockably mounting said head thereon, said trunnion passing through that portion of said head between the front of the head and its median point from front to rear, and mounting the head to engage said abutments evenly in a direction from front to rear when in a pressing position, and to swing its rear part downwardly and forwardly into an inclined position to provide easy access to its under face between pressing operations, and means connected to said head to move it between said positions.

9. In a swinging head press of the type in which a pressing platen is moved toward and from a pressing head, that improvement which comprises a frame having abutments near one end thereof, a head disposed below but near said abutments, a trunnion carried by said frame and extending in a direction from side to side thereof and rockably mounting said head thereon, said trunnion passing through that portion of said head between the front of the head and its median point from front to rear, and mounting the head to engage said abutments evenly in a direction from front to rear when in a pressing position, and to swing its rear part downwardly and forwardly into an inclined position to provide easy access to its under face between pressing operations, and a power operated motor mounted on said frame and coupled to the rear part of said head to swing the head selectively between its said positions.

10. In a swinging head press of the type in which a pressing platen is moved toward and from a pressing head, that improvement which comprises a frame having abutments near one end thereof, a head disposed below but near said abutments, a trunnion carried by said frame and extending in a direction from side to side thereof and rockably mounting said head thereon, said trunnion passing through that portion of said head between the front of the head and its median point from front to rear, and mounting the head to engage said abutments evenly in a direction from front to rear when in a pressing position, and to swing its rear part downwardly and forwardly into an inclined position to provide easy access to its under face between pressing operations, the contact between said abutments and said head extending more than one-half the distance between the front and rear margins of said head, and means connected to said head to move it between said positions.
